UNITED STATES PATENT OFFICE

2,508,619

MAGNETICALLY COUPLED GOVERNOR

Arthur N. Nilson, Chicago, Ill., assignor to Teletype Corporation, Chicago, Ill., a corporation of Delaware

Application July 8, 1948, Serial No. 37,621

7 Claims. (Cl. 318—325)

1

This invention relates to governors and more particularly to magnetically coupled governors for electrical apparatus.

An object of the invention is to provide an improved governor of simple design and construction which is particularly effective in controlling the speed of the driving motors of printing telegraph apparatus.

In the field of printing telegraphy it is of utmost importance that the transmitting and receiving apparatus be driven at the same rates of speed. In order to accomplish this it is most desirable that the speed of all the power devices in the telegraph system be maintained at a single constant speed. Accordingly, it is another object of the invention to provide a governor capable of maintaining the speed of rotation of an electric motor substantially constant.

A further object of the invention is to provide a governor which will operate with a minimum of friction and noise. Another object of the invention is to provide a governor which is readily adjustable in order to make it possible to vary the constant speed at which the motor is retained.

Another object of the invention is to provide a governor wherein a controlling member is positioned at least once during each revolution thereof solely by centrifugal force and during another portion of the revolution, the member, having been positioned by centrifugal force, is attracted towards one magnet or another to retain a switch in the motor circuit in either open or closed position during the remainder of the revolution.

These and other objects and advantages of the invention will be apparent from the following detailed description of the invention when read in conjunction with the accompanying drawing in which,

Fig. 1 is a side elevational sectional view of the governor forming the subject matter of the invention, and

Fig. 2 is a front elevational view.

Referring to the drawing, reference numeral 11 refers to a rotatable power shaft and a plate 12 is secured to a motor (represented only by a commutator 9 and brushes 10), the speed of which it is desired to govern. A casing 13 is suitably secured to the plate 12 to provide a housing for the governor mechanism. An insulator ring 14, made of any suitable insulating material, is secured to the plate 12 and supports a pair of collector rings 16 and 17. A lead 20A extends from a power source to the collector ring 16, a lead 20B extends from the collector ring 17 to one of the brushes 10, and a lead 20C extends from the other brush 10 to the power source.

A disc 18 is secured to the shaft 11 by means

2

of a bushing 19. A bracket 21 is firmly secured to the disc 18 and a stiff leaf spring 22 is secured to the bracket 21 by means of a bolt 23. An arm 24 is riveted to the leaf spring 22 and carries a motivating shoe 26. The arm 24 is movable pivotally slightly with the leaf spring 22 serving as a fulcrum, however, its movement is restrained by a pair of limiting stops 27. The arm 24 carries a contact point 28 which is adapted to cooperate with an adjustable contact point 29 carried by a bracket 31 suitably secured to the disc 18. The leaf spring 22 is insulated from the disc 18 and is electrically connected by means (not shown) to a brush 32 which rides the collector ring 16. The contact point 28 is suitably insulated from the disc 18 and is electrically connected (also by means not shown) to a brush 33 which rides the collector ring 17. It is therefore apparent when the contact points 28 and 29 are closed that a circuit is established to the motor which is being governed. This circuit is the power circuit to the motor.

A bracket 34 is secured to the disc 18 and has an aperture 36 therethrough within which a bolt 37 is slidable. The bolt 37 has a flattened portion 38 which is slidable and guided in an aperture 39 of a bracket 41 suitably secured to the disc 18. A tension spring 42 connects the bolt 37 to the arm 24 and the force of the spring 42 urging the arm 24 towards the center of the disc 18, or counterclockwise in Fig. 2 is readily adjustable by means of a nut 43 threaded to the bolt 37.

A magnet 44 is mounted securely to the casing 13 by means of a bolt 46 and secured to opposite ends of the magnet 44 are a pair of pole pieces 47 and 48. Each of the pole pieces 47 and 48 is in the form of a disc having an inner cylindrical segmental ring 49 and an outer cylindrical segmental ring 51. Each of the pole pieces 47 and 48 also have coadjacent cut out portions 52. The motivating shoe 26 is movable between the cylindrical rings 49 and 51 and the stops 27 are so positioned that the shoe 26 cannot engage either of the rings 49 or 51. The magnetic attractive force of the rings 49 and 51 for the shoe 26 is substantially the same for each ring and therefore while the shoe 26 is in a position between the rings it will be attracted towards the ring which it is nearer.

In the following description of the operation of the governor it is assumed that the motor shaft 11 is at rest. At this time the entire force of the spring 42 is urging the arm 24 inwardly so that the contacts 28 and 29 are closed. Therefore, when the main switch (not shown) in the motor circuit is closed, current is established to the motor.

As the motor, after being started, gains speed, centrifugal force acts on the motivating shoe 26 in a direction opposite to the force of the spring 42. During each revolution of the disc 18 and shoe 26, the shoe 26 is positioned solely by the balance of centrifugal force and the force of the spring 42 as the shoe passes the cut out portions 52 in the pole pieces 47 and 48. As the shaft 11 and disc 18 are accelerating to the proper speed the force of the spring 42 is stronger than the centrifugal force acting on the shoe 26 and arm 24, so that as the shoe leaves the cut out portions and enters the space between the rings 49 and 51, it is closer to the ring 49. Therefore, during that revolution the ring 49 attracts the shoe 26 to thereby retain the contacts 28 and 29 in closed relation for the remainder of that revolution. Upon the shaft 11 reaching the desired constant speed of rotation, centrifugal force operating on the shoe 26, while it travels in the cut out portion 52, is sufficient to move the shoe 26 outwardly so that upon entering the space between the rings 49 and 50, the shoe is nearer to the ring 51. Therefore, the force of magnetic attraction of the ring 51 on the shoe 26 is greater than that of the ring 49, so that the contacts 28 and 29 are retained in disengaged relation for the remainder of that particular revolution of the disc 18 and shoe 26.

The magnetic forces of attraction of both of the rings 49 and 50 are substantially equal and therefore the shoe 26 is attracted towards the ring which the shoe is nearer upon leaving the cut out portion 52 during each revolution. Only a slight variation in the speed of rotation of the disc 18 is necessary in order to enable the centrifugal force to move the shoe 26 sufficiently that the opposing magnetic ring 49 or 50 becomes effective.

Obviously, as the main motor switch is opened when it is desired to shut off the motor, during the deceleration of the shaft 11, the centrifugal force of rotation decreases so that the contacts 28 and 29 are retained closed. The circuit to the motor therefore is always in condition to start the motor whenever the main motor switch is closed subsequently.

It will be understood that the embodiment of the invention shown and described is merely illustrative of the principles involved and numerous modifications and changes may be made without departing from the spirit of the invention.

What is claimed is:

1. In a control device for electrical apparatus having an electrical power circuit, a centrifugally and magnetically positionable member, a first magnetic means for attracting said member to cause a closure of said power circuit, and second magnetic means for attracting said member to cause a break in said power circuit, the effectiveness of each of said magnetic means being determined in accordance with the positionment of said member by centrifugal force.

2. In a governor for electric motors, a member positionable by centrifugal force at least once during each revolution of the motor shaft, a first magnetic means for attracting said member to cause a closure of a power circuit to the motor, and a second magnetic means for attracting said member to cause a break in the power circuit, the effectiveness of each of said magnetic means being determined in accordance with the positionment of said member by centrifugal force.

3. In a governor for an electric motor, a power circuit to the motor, a switch in said power cir-

cuit, a movable member for controlling the operation of said switch, said member being positioned at least once during each revolution of the motor shaft by centrifugal force, a first magnetic means for attracting said member to cause a closure of said switch, and a second magnetic means for attracting said member to cause an opening of said switch, the effectiveness of each of said magnetic means being determined in accordance with the positionment of said member by centrifugal force.

4. In a control apparatus for power devices, a movable member for controlling the power supply to the power device, said member being positioned by centrifugal force during a portion of each revolution of the power device, a motivating shoe on the movable member responsive to magnetic forces, and a pair of segmental magnetic rings between which said motivating shoe is designed to rotate, said centrifugal force being effective to position said shoe nearer to one of said rings than to the other whereupon the nearer ring is effective to attract said shoe and thereby control the power supply during the remainder of that revolution.

5. In a governor for electrical apparatus, a rotatable motivating shoe, a switch in the circuit of the electrical apparatus operable in accordance with the radial positionment of said shoe relative to its axis of rotation, and a plurality of concentric cylindrically shaped magnets having coadjacent cut out portions therein, said shoe being adapted to rotate between said magnets and to be positioned solely by centrifugal force when rotating in said coadjacent cut out portions, a group of said magnets as determined by the centrifugal positionment of said shoe being effective upon the entry of said shoe between said magnets to attract said shoe and thereby control said switch during the remainder of that revolution of said shoe.

6. In a governor for electrical apparatus, a pair of relatively movable contacts, centrifugally responsive means for controlling the relative positions of said contacts at least once during each revolution of a power shaft of the electrical apparatus, and magnetic means effective during the remainder of each revolution for maintaining said contacts in open or closed relation according to the relative positions of said contacts as determined by said centrifugally responsive means.

7. In a governor for electrical apparatus, a pair of relatively movable contacts, centrifugally responsive means for controlling the relative positions of said contacts at least once during each revolution of a power shaft of the electrical apparatus, a first magnetic means capable during the remainder of each revolution to maintain said contacts in open relation, and a second magnetic means capable during the remainder of each revolution to maintain said contacts in closed relation, the effectiveness of either of said magnetic means being dependent upon the relative positions of said contacts as determined each revolution by said centrifugally responsive means.

ARTHUR N. NILSON.
